UNITED STATES PATENT OFFICE.

WARREN R. GREENLEE, OF PASADENA, CALIFORNIA.

METHOD OF AND SYSTEM FOR PUMPING.

1,310,615.

Specification of Letters Patent. Patented July 22, 1919.

Application filed October 28, 1915. Serial No. 58,337.

To all whom it may concern:

Be it known that I, WARREN R. GREENLEE, a citizen of the United States, residing in Pasadena, in the county of Los Angeles and

5 State of California, have invented a new and useful Method of and System for Pumping, of which the following is a specification.

In general, an object of this invention is to facilitate obtaining liquids from the earth. 10 Another object is to cheapen the production of liquids such as oil and its associated products.

Another object is to effect the foregoing by making provision for control of the fluids 15 to be tapped by the well while drilling, pumping and cleaning the well. This provision is made for wells pumped by piston pumps, flowing wells and also wells pumped by fluid from an external source, alone or in 20 combination.

Another object is to make provision for conserving all of the products given off through the well.

Another object is to make provision for 25 utilizing to the maximum without wastage the hydrostatic and gas pressures in the producing stratas.

Another object is to make provision for establishing and maintaining or renewing 30 the ratio of gas and liquid volumes requisite to produce a flow.

Another object is to prevent plugging of the well by sand and mud.

Another object is to distil as much of the 35 valuable condensates, such for instance as gasolene, from the gas as possible and then to utilize the resulting comparatively dry gas to flow oil from those wells that may be deficient in the volume of gas requisite to 40 flow the oil from said wells, or aid the piston in its pumping action in a piston-pumped well.

It is understood that the term "pump" 45 and "pumping" define and imply any device and operation whereby liquid is caused to issue from the earth.

In some of the most prolific oil producing fields of the world, experience has shown that big producing wells cannot be pumped 50 successfully because sand or mud invariably enters and chokes the valves, pump and tubing and even plugs up the well itself. This is especially the condition frequently found in the oil fields of California, and the fact 55 that the wells in the California oil fields

are usually of such great depth as well as being drilled into loose sand and shale makes the pumping of them the more difficult.

Without the use of this invention, when the oil together with a large volume of gas 60 is contained in producing strata such as loose sand and shale, the head or rock pressure of the gas and oil for an interval of time drives said gas and oil through the sand and shale formation and into the well and 65 the pressure is often so great that large quantities of the sand and shale, and in some instances mud, are carried into the well by the velocity of the oil and gas. The resistance that the well offers to escape of the oil 70 and gas therefrom is less than the resistance which the oil and gas encounter in the rock or ground formation, hence after a great flow and heave of oil and gas into the well and therefrom and, after the head of oil is 75 thus blown out of the well, the pressure in the well subsides for another interval of time until enough oil and gas is forced through the sand and shale to cause another flow. But before another flow can occur, 80 the column of said sand and mud, remaining in the well after the flow has ceased, settles down into the bottom of the well, packing the pump tubing and forming bridges and even choking the well solidly near the bot- 85 tom. When there is water mixed with the oil, said water cuts the mixture and lets the sand settle quicker and the clean sand packs with extreme firmness.

After the interval of time of non-flow another heave or rush of oil, gas, sand and shale or mud occurs to fill the space left by the oil, sand and gas that has escaped into the well. The renewed pressure will do one of two things, either blow out the sand 95 plugs and thereby enable the oil and gas to gush out of the well as before, or else, as is quite as often the case, said pressure compresses the plug of sand, shale and mud into a still tighter plug, thereby effectually plugging the well and stopping the production of oil therefrom until the well has been cleaned by the use of tools or until the pipes have been pulled. This cleaning of the well and pulling of the pipes is of such frequent 105 occurrence that the cost of production of oil is often so great that even gusher wells frequently are not as profitable as smaller capacity wells.

To avoid the plugging, screening has been 110

resorted to in many instances, but screening reduces the out-put of the well because holding back the sand retards the oil on account of the viscosity of the oil. It follows from this that to get a good flow of oil it is absolutely necessary to allow the sand and shale to enter the well with the oil and gas.

Another method whereby to get rid of the sand has heretofore been tried by use 10 of the air lift but this method has certain disadvantages and cannot be applied to a well that will not flow because of lack of proper submergence and furthermore the power expended in the air lift makes the air 15 lift method too expensive unless it is possible to produce a continuous flow, which is very seldom the case. Wells are often able to furnish more than enough gas under high pressure to flow all the oil that said wells 20 can produce, and therefore to use the air lift with such wells is obviously a waste of power.

Hydraulic pumping has also been tried but since in hydraulic pumping the pressure 25 of the hydraulic fluid is almost invariably greater than the rock pressure, the greater pressure causes sand bridges to be produced in the casing and thus partially or entirely plug up the well. Hydraulic pumping is 30 also very apt to pack the mud and sand into the producing sands around the bottom of the well so tightly as to practically seal said sands and stop the flow of oil therefrom, the sealing being so effectual sometimes that it is impossible to dislodge it so 35 as to allow the oil to again flow.

Only in comparatively few instances is there any relief from a badly sanded well, for cleaning it with tools and pulling the 40 pump tubing only enable the well to flow temporarily and often the casing collapses or is broken off by the caving roof of the cavity created around the well, thus entailing additional expense in the redrilling 45 thereof.

From the foregoing it is clear that at best most big producing wells entail tremendous expenses while they are big producers, such expenses often preventing the well from being 50 profitable and involving the owner of the well in pecuniary losses.

It is clear that the difficulties outlined above are all due entirely to the uncontrolled pressures and great fluctuations in 55 the velocity of the oil and gas flowing through the sands in the immediate vicinity of the well and in the well itself, and also to the fact that prior to this invention the fluctuations in the velocity have been entirely 60 uncontrolled. To overcome these difficulties and others which may appear hereinafter I make provision whereby the velocity of the oil and gas will remain steady, constant and as uniform as possible and 65 whereby the pressure in the well and the

head or rock pressure will nearly balance one another. Inasmuch as the relative pressures control the velocities I am enabled by altering the pressures to obtain higher or lower velocities as desired.

This invention not only makes provision for controlling the pressures and velocities in a well but, also, makes provision for obtaining continuous flow of oil and gas in many instances, when such would not be the case without such provision, so as to minimize the liability of choking and plugging of the well and its equipment by sand, shale, mud and the like, and also minimize liability of packing the producing earth strata 80 around the well.

It is noted that great oil gushers generally become extinct in a short time, and that this is due to the plugging and packing of the sand as outlined above is verified by the 85 fact that good producing wells have been sunk close to extinct gushers.

Whether or not the wells are gushers or are ordinary flowing or piston-pumped wells, said ordinary flowing and piston 90 pumped wells intermittently have the same great pressures as the gushers and are therefore liable to be plugged up by sand and shale as above described unless provision is made for their control.

A further harmful effect of the alternate higher and lower pressures of the oil and gas flowing into the well and consequent rise and fall of the level of liquid in the well is that erosion of the well takes place, thus inducing caving-in of the walls and roof of the well cavity, such caving-in producing crushing or breaking of the casing so that shooting the well and then redrilling is necessary. This shooting and drilling 100 operation further breaks up the formation and encourages caving. Even this operation is difficult in a great many instances for the sand often enters the well as fast as the tools can clean it out of the well, thus making it very difficult on account of the presence of the sand to cut the casing or even blow it off near the sand by blasting, and hence the greater portion of the string of casing is usually lost. A still further harmful effect of a blow-out is that when the great pressure due to the head of oil in the tubing is removed much of the gas in solution in the oil becomes free to expand and rise and escape therefrom, so that the oil 110 subsequently filling the well is deficient in gas or "dead" and can not flow for a comparatively long period of time.

To effect the foregoing objects and to overcome the difficulties outlined above 125 there is provided either a pressure regulated valve or valves, such for instance as a diaphragm valve, at the top of the well; or pressure regulated valves, at various levels in the well, or both, to establish, maintain or 130

renew the ratio of liquid volumes and pressures or the ratio of gas and liquid volumes and pressures requisite to produce flow.

- One of the valves at the top of the well 5 opens and closes at predetermined higher and lower constant differences of pressures of gas and oil in the well to open the oil discharge pipe and permit the oil to flow and to close the oil discharge pipe until the 10 pressure reaches the predetermined higher constant differences of pressure when the valve again opens to permit the oil to flow. Another of the valves at the top of the well opens and closes at predetermined 15 higher and lower constant differences of pressures of gas in the well to admit fluid to and exclude fluid from entering the well from an outside source such as a gas well, compressor or pump.
- 20 These valves just mentioned may be combined or used separately if desired.

- The valve or valves at the top of the well 25 may be suitable and satisfactory for a certain small class of wells and, though the well is under control and can not blow out the head of oil so as to cause the difficulties hereinbefore set forth as resulting from the blow-out, yet for another larger class of wells it is more desirable to place the valves 30 at different levels in the well, and by so doing certain advantageous results are obtained that cannot be obtained by the valve or valves at the top of the well without complicating and increasing the cost of the 35 equipment.

- When the valves are placed at various levels in the wells, they automatically control entries at all of said levels, the flow of liquid taking place at one level or another 40 according to the variations in the volumes and pressures of gas flowing to the well in some instances with the oil and in part according to variations in the pressure of liquid to be pumped at the level of each entry, or according to the variations in the 45 volumes and pressures of fluid, either gas, or liquid, flowing or forced into the well in other instances at the top from an external source of supply.

- At lower pressures the higher valve may have flowing submergence and in such event opens to admit the operating fluid to flow the well; and at higher pressures, when there is nonflowing submergence of said higher 5 valve, the higher valve closes to exclude the operating fluid and the lower valve may then have flowing submergence and in such event opens to flow the well; and at still higher pressures, when there is nonflowing 10 submergence of the lower valve, the lower valve closes to exclude the operating fluid. Closing of the valves and thus excluding the operating fluid from the pump tubing when there is nonflowing submergence of the valves insures that said operating fluid

will be held in storage in the well to aid subsequent flowing of the well and prevents by its back pressure the harmful velocities and heaves hereinbefore referred to. Thus each valve shuts to exclude the operating 70 fluid when there is nonflowing submergence of said valve and if said fluid is a gas prevents blowing off and wastage of said gas and dissipation of its energy. One advantage of what I term plural or multiple entries is that, when the gas pressure is 75 low in the well and the oil level is comparatively high, the well will flow with lesser submergence than otherwise required, thus enabling the well to be flowed by low pressure 80 fluids. This is of course a great economy and is also of advantage in starting a well to flow.

From this it is seen that low pressure gases and small volumes of gas can be utilized to effect flowing, and that, no matter how low a pressure of gas is furnished by a well, said gas is effective in displacing an equivalent volume of oil and thereby reducing the load on the piston in a piston-pumped well in proportion to the amount of the displacement.

Other advantages of the plural or multiple entries are that in a piston-pumped well no free gas can enter the pump and thereby reduce the output of the well and the gas cannot enter the pump cylinder and keep the valves closed so that the pump piston will merely work against a gas body.

Another advantage of the plural entries 100 is that with deep submergence and small volumes of high pressure gas, when the smaller volumes of high pressure gas change to larger volumes of low pressure gas, said low pressure gas becomes available to flow 105 the well.

Heretofore to obtain at the start the greatest pumping efficiency it has often required trials at different submergences, and it follows from this that to maintain the 110 greatest efficiency it would be necessary with many prior devices to raise and lower the pump to meet all variations in the level of the liquid in the well. By the plural entry construction the pump is self adjusting to 115 the different levels and pressures and therefore the pump is always working under maximum efficiency.

By maintaining the gas pressure it is clear that all of the gas dissolved in the oil is held 120 in solution, so as to insure that the well will always contain "lively" oil capable of hastening the flow.

Heretofore some oil wells were each equipped with a string of tubing and a rubber packing near the lower end of the tubing so as to cause all of the gas to flow into the string of tubing and thus displace and flow the oil. Thus heretofore there was no control or utilization of the gas to produce a 130

steady flow of the liquid in the well so as to prevent the rush of gas and consequent plugging of the well and producing sands therearound as hereinbefore outlined, and 5 there has been no provision for conserving the natural rock pressure in the gas fields. The gas has been allowed to come out of the well at random so as to bring the oil with it and after the head of oil blew out the 10 gas was allowed to blow off until the oil accumulated for further flow. The intermediate nonflowing periods entailed the loss of a tremendous amount of energy besides the risk of producing sanding of the well 15 and tubing and shortening the life of the well. After the rock pressure was allowed to waste away expensive pumping was often resorted to to obtain the oil left dead in the well.

20 In carrying out this invention, in order to obtain full control of the pressures and velocities, I first insure perfect sealing of the well. Wells have not heretofore been perfectly sealed and this is substantiated by 25 the fact that water wells several miles away from an oil field have been contaminated by seepage of oil and gas from the oil wells through the nonproducing strata above the oil sand to the water wells. The casing 30 above the producing strata is surrounded by a sealing ring of cement or the like.

I provide either a gas-tight casing head at the top of the well or a packer set at an intermediate point in the well so as to form 35 a pressure-fluid reservoir between the casing and tubing below the casing head or packer as the case may be. The gas or other operating fluid is taken from the reservoir as needed to displace the oil in 40 the tubing and cause the same to flow out of the well, and if gas is the operating fluid being used any gas in excess of what is necessary to cause the oil to flow at a velocity that can be readily taken care of is discharged and utilized in another well or wells 45 having insufficient volumes of gas to displace the oil and cause the same to flow. Thus the reservoir forms a gas trap or receiver adapted to contain an elastic cushion 50 of gas that insures against violent changes of pressure at all times, thus preventing excessive sand and mud heaves and consequent plugging and clogging of the well, its equipment and the producing sands.

55 A comparatively slight displacement of oil between the casing and tubing by the pressure of gases in the reservoir causes much greater displacement of the oil in the tubing so that it will rise therein, the level 60 rising until the head of the column of oil in the tubing balances the pressure of the gas in the reservoir or gas trap. The head of the oil and the gas pressure continue to balance one another until sufficient oil ac- 65 cumulates in the well to cause flowing sub-

mergence, whereupon the oil will flow in a manner well understood.

Thus it is clear that if the well at all times furnishes the requisite amount of oil and gas to produce a flow, said flow with 70 this invention will be steady and continuous. This invention makes it possible to conserve the much needed gas in the well at the precise moment it accumulates in greatest abundance, and unless such provision were 75 made said gas would blow out to little or no purpose, the blow out of gas occurring just before and after the head of oil has been blown out of the well. Such total release of the pressure in the well and on the sand 80 near it allows an in-rush of gas which is lost and a flow of oil with such violent velocity as to result in the disastrous sanding and other objectionable results hereinbefore outlined. Even when there are no shifting 85 sands to plug the well, the well without this invention remains dead until sufficient gas collects to cause flowing pressure.

The distance above the sand at which the gas entry or entries are located de- 90 termines the depth of submergence and also determines the head of the fluid or equivalent gas pressure carried by the well to be utilized to balance the rock pressure. To prevent gas blow-outs the length of the tail 95 pipe may be made directly proportional to the pressure desired to be carried by the reservoir or said tail pipe may be provided with a puppet or check valve.

The regulator or entry valves are so con- 100 structed as to automatically control the volume of gas or other operating fluid passing through said valves and furthermore are so constructed as to regulate said volume and maintain the ratio of the operating 105 fluid and oil volumes, the ratio of said volumes remaining the same but the rate of flow changing according as the total volume of the operating fluid and oil is greater or less.

If with the use of this invention the flow of oil ceases because of insufficiency of either oil or gas or both, there is always a possibility of sand in the oil in the tubing settling down and bridging across and plugging the tubing. If this occurs, another great advantage of the valved multiple entries becomes evident, for by releasing some of the gas at the top of the well and thus reducing its pressure an entry above the 120 sand plug will open and admit oil to the tubing and another entry or entries higher up will open to admit gas which will cause the oil above the plug to flow. The weight of the oil column above the sand plug will thus tend to be gradually diminished and when it is so diminished said sand plug will be blown out by the pressure of oil and gas beneath it. If there is flowing submergence 125 and the pressure of gas is so great as to close 130

the valves at all of the entries, then some of the gas may be released at the top of the well from the reservoir to lower the pressure sufficiently to allow the head of oil 5 in the tubing by its head to open the lower valve so that the oil will flow.

It is understood that, when fluid under pressure is supplied to the well from an external source to effect the pumping or flow 10 of the liquid tapped by the well, said fluid may be gas taken directly from another well under pressure or may be gas from a compressor and this gas may be compressed air, or said fluid may be a liquid taken from 15 the well itself or taken from an outside source.

Heretofore the gas in the well rising with the oil and discharging therewith resulted in waste of power for, if the oil was not 20 discharged against pressure greater than atmospheric, the gas expanded and so lost its expansive energy; and, if the oil was discharged against said greater pressure, as is often the case, then the pump had not 25 only to work against the head of oil in the tubing plus the atmospheric pressure but against said head plus the greater pressure. To avoid such waste of power I provide 30 means in the form of a gas trap to separate the gas from the oil and remove its pressure from the oil, thereby maintaining the gas under whatever pressure it has at the point of discharge of the oil without causing back pressure of the gas against the oil in 35 the tubing.

This is effected by placing the trap at any appropriate point in the well above 40 the submergence level to deliver the gas at a high pressure to the surface and reduce the "lift" or regular pressure in the well, thus drawing off gas, which if left in the tubing would expand and produce a great 45 degree of friction in the tubing and consequent back pressure load against the pumping force.

The gas trap, if desired, may be positioned below the submergence level to deliver the gas at higher pressures, but of course the "lift" or regular pressure would thereby 50 be increased.

The accompanying drawings illustrate the invention:

Figure 1 is an elevation partly in section of an apparatus whereby the novel method 55 is carried out, portions of the well equipments being broken away to contract the view. The engine and its driving connections for operating the sucker line of well *d* are broken away to contract the view. 60 For purposes of illustration the well equipments are shown of larger size relative to the size of the distilling, cooling and compressing plants than they would be in practice.

Fig. 14 is an enlarged sectional elevation on line indicated by $x^{14}-x^{14}$, Fig. 13.

There are provided wells *a*, *b*, *c*, *d*, *e*, *f*, *g* and *h* tapping the oil-producing earth strata indicated at *k*. Each well is provided with a casing or conductor tube 1 having oil and gas inlet perforations 2 and provided outside of said casing above said perforations and above the producing strata with a sealing ring 3 of cement, or the like, to prevent oil and gas from the producing strata *k* seeping through the non-producing strata *m* above said producing strata and thus escaping, and to prevent water entering the 100 producing sands.

Each casing 1 is provided at its top with a gas tight casing head and cover 4, 5 of suitable construction, the casing head and cover shown in the drawings not being described in detail and claimed herein but being the subject of my copending application for patent for well equipment filed January 29, 1916, Serial No. 75,113. 110

Interiorly each casing 1 with the exception of the one in well *f* is provided with pump tubing 6 and each tubing is provided at intervals therealong with operating-fluid entry members shown more clearly in Figs. 2 to 6 inclusive and constructed as follows: 115

Each entry member comprises a barrel 7 into which is screw-threaded the adjacent ends of sections of the pump tubing 6 so as to form a continuous tubing, and also comprises an entry valve jacket 8, an inlet passage 9 and a check valve chamber 10; said valve jacket and inlet passage communicating with one another through a port 11 and said valve jacket communicating with the barrel through upwardly and inwardly in- 125

130

clined ports or entries 12 and said valve jacket and check valve chamber communicating with one another through a port 13. The ports or entries 12 at the different 5 levels constitute what I term plural or multiple entries.

The lower and upper ends of the valve jacket are closed by plugs 14 and the upper ends of the check valve chambers 10 are 10 closed by plugs 15.

Each jacket 8 excepting the lowermost one in the well *e* is provided internally with a threaded shoulder 16 engaging a threaded bushing 17 on the upper end of a longitudinal 15 ribbed ball chamber 18 having in its interior a valve ball 19 adapted to close on to a lower seat 20 when the ball is in its lower position, as in Fig. 2 and adapted to close on to an upper seat 21 when said ball 20 is in its upper position as in Fig. 4. The upper seat 21 may be provided with means such as notches 22 to allow a slight flow of operating fluid through the valve and into the pump tubing so that, if the well 25 is not discharging liquid, any sand that may be in the liquid will be agitated and maintained in suspension in the liquid by the slight flow of said fluid to prevent the formation of bridges and plugs tending to 30 choke the pump tubing.

To close on to the upper seat 21 from its lower position, each ball 19 must first strike the lower cupped end 23 of a stem 24 and move said stem against the pressure of a 35 coiled expansion spring 25 which is seated at one end against tension adjusting nuts 26 adjustable along the stem 24, said spring being seated at its opposite end against the upper end of a cage 27 that surrounds said 40 spring. The stem 24 is screw-threaded at its upper end to adjustably engage an abutment formed by a nut or nuts 28, one of which engages the upper end of the cage to maintain the cup 23 at a predetermined 45 adjustable distance from the valve seat 20. The nuts 28 may be engaged by a tool (not shown) to turn the stem 24 and thereby adjust the nuts 26 relative to said stem to increase or diminish the tension of the spring 50 25, said nuts 26 being held against turning by pins 29 projecting from the nuts between adjacent ribs of the cage. The cage 27 is screw-threaded at its lower end into the bushing 17.

55 Each ball chamber 18 is inwardly tapered from its middle portion toward its ends so that the inside diameter of said chamber is gradually reduced from its middle portion to the valve seats 20, 21.

60 Each of the check valve chambers 10 is provided at its lower end below the level of the port 18 with a ball check valve 30, said valve operating to admit fluid from the casing 1 to the check valve chamber 10 65 but preventing back discharge of fluid from

said chamber into the casing so as to prevent back pressure of the operating fluid against the fluid in the producing sands.

In the wells *a*, *d*, *e*, and *g* the inlet passages 9 are connected to one another and 70 the topmost gas passage in each of said wells is connected with the casing head lid 5 by sections of an operating fluid conductor tube 31 so as to form a straight continuous fluid conductor. Because of the provision of the 75 check valves 30, it is clear that any desired pumping pressure of the operating fluid in the wells *a*, *d*, *e* and *g* may be employed without liability of forcing the gas and liquid being pumped back into the producing 80 strata. The advantage of this is that the well piping may readily be cleaned of sediment, if it becomes clogged up under the ordinary pumping pressures, by using much greater pressures of the operating 85 fluid.

In all of the wells excepting well *f* the spaces between the casings 1 and tubings 6 form reservoirs, traps or receivers *o* of which the tops are formed at the upper ends of 90 the casings 1 by the casing head lids 5 for wells *b*, *d* and *h* and are formed at any desired intermediate portion of the wells *a*, *c*, *e* and *g* by suitable packers 32 and 32'. In the well *c* the packer 32 has the same effect as 95 the check valves 30 in the wells *a*, *d*, *e* and *g* to keep the pressure of the operating fluid off of the producing strata. The packer 32 is not described in detail and claimed herein but is the subject matter of my copending 100 application for patent for well equipment filed January 29, 1916, Serial No. 75,113.

From the foregoing it is seen that the valve balls 19 are normally closed on the seats 20 when there is not enough pressure 10 of the operating fluid to overcome the pressure of the column of liquid in the pump tubing above the respective valves, thus preventing liquid and sand from backing down through the ports 12 and thence through the 11 valves which thus function as check valves; and that each valve will open under pressures of the operating fluid sufficient to displace the liquid above said valve; and that said operating fluid will discharge upward 111 and inward through the ports 12 into the tubing 6 to flow the liquid in the tubing when there is flowing submergence of the valve; and furthermore that, if the pressure of operating fluid is sufficient to force the 120 valve ball 19 against the pressure of the spring 25 to close on to the seat 21, closure of the valve will exclude the operating fluid from the tubing in any but very small volumes.

The tapered ends of the ball chambers 18 have this effect, that, if the pressure of the operating fluid is just sufficient to raise the ball 19 a slight distance above its seat 20 against the head of liquid in the pump tub- 130

ing, a comparatively small volume of said operating fluid will flow through the valve, thus conserving the supply of said fluid and effecting a comparatively small flow of liquid in the tubing; that, if the pressure of the operating fluid is higher and thereby raises the ball to the intermediate portion of the ball chamber, where said chamber is of greatest diameter, against the head of liquid in the tubing, a much greater volume of the operating fluid will flow through the valve to effect a greater flow of liquid; and furthermore that if the pressure of the operating fluid is still higher, in fact so high as to endanger flowing out the head of liquid in the tubing, said still higher pressure will act to raise the ball 19 against the expansive force of the spring 25 into the reduced upper portion of the ball chamber 18 to diminish the flow of the operating fluid or, if said still higher pressure is greater than can safely be used without blowing out the head of liquid in the tubing, then the still higher pressure will act to shut the ball on to the seat 21 to exclude all but a relatively minute volume of operating fluid from the pump tubing at the entry thus shut off. It is understood that owing to the load of liquid on the valve being greater the lower the valve is, the valves may open and close successively so as to maintain the ratio of operating fluid and liquid volumes, though the rate of flow may change according as the total volume of the operating fluid and liquid being pumped is greater or less.

From the foregoing it will now be clear that the pressures in determining whether or not the entry valves are to be in open or closed position are variable, and that the constant difference which determines the valve operating pressure is predetermined by the levels at which the inlet valves are placed and the strength of the springs 25.

The well *a* is provided with a gas trap shown more clearly in Figs. 7, 8 and 9 and constructed as follows: One section 33 of the pump tubing 6 is screw-threaded into the inlet 34 of one head 35 of a cylindrical container 36 having at its upper end another head 37 through which another section 38 of the pump tubing passes into the interior of the container, said section 38 having its lower end spaced apart from the head 35. The lower end of the tubing section 38 is connected by a collar 39 to a valve chamber 40 containing a check valve ball 41 designed to close on to a seat 42 in the lower portion of the valve chamber. The valve chamber 40 is spaced apart from the lower head 35 and a nozzle 43 is screw-threaded into the inlet 34, said nozzle being provided with a portion 44 extending upward along one side of the valve chamber 40 above the level of the valve inlet 45 so as to form a trap. The liquid is enabled to pass from said trap

through the pump tubing section 38 and the trapped gas passes from the container 36 through a gas pipe 46 which communicates with the interior of the container through the head 37 and which is provided with a fluid-pressure regulator or valve 47.

By the use of the device just described gas under pressure after it has performed the work of lifting fluid to the upper portion of the well is trapped and the energy due to the pressure is thus conserved.

It is also noted that by the use of this gas trap at the upper portion of the well, not only is the discharge pressure of the gas maintained but there will be no back pressure of the gas against the liquid being pumped, thus the pump will only need to work against the head of liquid in the tubing and not against said head plus the back pressure of gas.

The pump tubings 6 communicate through the casing head lids 5 and discharge pipes 48 with an oil pipe line 49 which connects with a gas trap 50.

There are provided a battery of tubular stills 51, 52, 53, 54, tubular vapor stills 55, 56, tubular condensers 57, 57', 57'', 57''', storage tanks 58, 59, 60, final storage tank 61, sump 62, a tubular separator 63 for separating the water and sand from the oil, dephlegmators 64, 65 for separating the oil and gas from one another, dirt trap 66, ammonia gas compressor 67, two stage gas compressors 68, 69, 70, 71, 71', ammonia tank 72, freezing vat 73, drip tanks 74, 75, 75', 76, 77, coolers 78, 79, 80, 80' and a cooling tower 81.

The oil line 49 connects to the gas trap 50, thence connects to the separator 63.

The storage tanks 58, 59, gas trap 50, condensers 57, 57', 57'' and the casing head 4 of the well *a* connect to a gas line 82, and the separator 63 connects to the storage tank 58, 59, and said storage tanks connect to one another.

The gas line 82 passes through cooler 79, thence passes through cooler 80, thence connects to compressor 68, thence passes through cooling tower 81, thence connects to compressor 70, thence passes through the cooling tower 81, thence connects to drip tank 75, thence passes through the cooling tower 81, thence connects to the drip tank 75', thence connects to condenser plant 57''', thence connects to the second stage of compressor 70, thence passes through cooling tower 81, thence connects to drip tank 76, thence passes through cooling tower 81, thence connects to compressor 71, thence passes through cooling tower 81, thence passes through coolers 80', thence passes through drip tank 77, thence connects to the compressor 71' to operate said compressor, thence passes through the coolers 80' to cool them, thence connects to the compressor 71', 130

and said gas line connects from the drip tank 77 to a fluid-pressure regulator or valve 83, thence connects to the second stage of the compressor 71 which is connected to 5 a high pressure gas line 82' that passes through the cooling tower 81, thence passes through the cooler 78, thence passes through the freezing vat 73, thence connects to the drip tank 74, thence connects to the casing 10 heads 4 of the wells *a*, *b*, *c*, *d*, *f*, *g*, and to the conductor tubes 31 of the wells *a*, *d*, *e* and *g*.

The casing heads 4 of the wells *e*, *f* and the dephlegmator 65 connect to a gas line 15 84 to supply gas thereto. The gas line 84 connects to the gas line 82 between the dephlegmator 65 and cooler 79 and connects to the gas line 82 between the compressor 71 and the cooling tower 81 and 20 also connects to the compressor 69 and to the gas line 82'.

The oil line 49 passes from the separator 63 and connects to the stills 51, 52, 53, 54 in series, thence connects to the header 85 of 25 the tubular separator 63, and connects from the header 86 of said tubular separator to the storage tank 60, thence connects to a pump 87, thence connects to the storage tank 61.

30 The trap 88 of the separator 63 connects to the sump 62 which connects to a pump 89, that in turn connects to storage tanks 60, 61.

The still 51 connects with the pipe 90 35 passing through the still 55 to the condenser 57; and the still 52 connects by pipe 91 with the dephlegmator 64 which connects with pipe 92 passing through the vapor still 56 to the condenser 57'; and the 40 vapor still 53 connects by a pipe 93 to the pipe 92; and the still 54 connects by a pipe 94 to pipe 93.

The pipe 90 is connected to the pipe 92 by a pipe 95. The pipe 94 connects to the 45 headers 96 of the tubular stills 51, 52, 53, 54, and to the engine exhausts of the compressors 70, 71, and to the header 85 of the separator 63, and to the engine exhaust of the pump 89. The condenser 57 is connected 50 by a pipe 97 to the pipe 46.

Water from the sump 62 is sucked through a pipe 99 by the pump 89, and forced thereby through a pipe 100 to the separator 63, thence through a pipe 101 to the trap 88, thence through a pipe 103 to a pump 104, thence through a pipe 105 to the sump 62.

55 The tubings 6 of the wells *d* and *g* are provided with pistons 106, 107 operated by sucker lines 108, 109 respectively, said 60 sucker line 109 being operatively connected to a pump 110 which is connected by its discharge pipe 111 to the conductor tube 31 of the well *e* and to the casing head 4 of the well *g* and which is connected by intake

pipe 112 to a suitable source of liquid supply, as the tank 61.

The pump 110 is provided with an air chamber 113 connected by a pipe 114 to a pressure operated alarm device 115.

The ammonia gas compressor is connected 70 by pipes 116, 117 to the freezing vat 73 and ammonia tank 72 respectively and the freezing vat is connected by pipe 118 to the ammonia tank.

The oil line 49 is provided with check 75 valves 119, 120 between the separator 63 and tank 59; and the discharge pipes 48 are provided with check valves 121; and said oil line is provided with combination check valves 122 between the separator 63 and 80 still 51, stills 51 and 52, 52 and 53, 53 and 54 respectively. The gas discharge pipe 46 is provided with a check valve 123 and the gas line 82 adjacent the well *h* is provided with a check valve 124. The gas line 84 85 is provided between wells *e* and *f* with a check valve 125, and between the well *f* and the compressor 69 and gas line 82 with a check valve 126. The pipe 111 is provided between the pump 110 and wells *e*, *g* with 90 check valves 127, 128 respectively.

The discharge pipe 48 and the gas line 82' adjacent the well *e* are provided with fluid-pressure regulators or valve 129, 130 respectively connected by pressure pipe 131 95 to the gas line 82' and said gas line is provided with a by-pass pipe 132 passing around the regulator 130.

The gas line 84 is provided between the wells *e*, *f* on one side and the gas line 82 100 and compressor 69 on the other side with a balanced fluid-pressure regulator or valve 133, said regulator being connected by pressure pipes 134, 135 with the gas line 84 on the well side and compressor side respectively.

The gas line 82' is provided between the dephlegmator 65 and the wells with a fluid-pressure regulator or release valve 136.

In the well *a* the distinguishing peculiarities are the inlet members at different levels connected with one another by the conduit for the operating fluid, and the gas trap for separating some of the high pressure gas from the oil. In the well *b* the distinguishing peculiarities are the inlet members at different levels receiving the operating fluid direct from the well casing. In the well *c* the distinguishing peculiarities are the inlet members at different levels receiving the operating fluid direct from the well casing, and the packer to separate the well casing into upper and lower chambers. In the well *d* the distinguishing characteristics are an inlet member connected to an operating-fluid conduit and a piston for pumping, or aiding in pumping, the oil. In the well *e* the distinguishing peculiarities are 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950

the inlet members at different levels connected to one another by the conduit and the packer through which the conduit extends. In the well *f* the distinguishing 5 peculiarities are that it is devoid of pumping mechanism and merely furnishes gas to the system. In the well *g* the distinguishing peculiarities are the inlet members interconnected by the conduit, the piston for 10 pumping or aiding in pumping the well, and the pump for forcing liquid into the conduit to cause the circulation of liquid through the conduit to prevent clogging of the same with sediment. The well *h* is just 15 an ordinary oil well provided with pump tubing and the gas-tight casing head 5. The pump tubing in the well *h* may have a single inlet as is usual in prior constructions.

In practice if the wells *a*, *b*, *c*, *d*, *e*, *g* have 20 sufficient volumes of gas and liquid to produce natural flow, the gas will flow through the check valves 30 of the lowermost entry members into the chambers 10, thence through the ports 13 to operate the valve 25 balls 19 as hereinbefore described and also through the ports 11 and passages 9 into the conductor tubes 31 in the wells *a*, *d*, *e* and *g* and into the conductor tubes 1 in the well *b*, and thence to the other entry members 30 to flow the liquid in the tubing at the levels where proper submergence and pressures are. If the wells lack sufficient volume of gas to produce natural flow, gas from the pipe line 35 82' will enter the conductor tubes 31 of the wells *a*, *d*, *e*, *g* and tubes 1 of the wells *b*, *c* to flow the liquid in the tubing at the levels where proper submergence and pressures are.

If there is more than sufficient gas in any 40 of the wells *a*, *b*, *d*, *e*, *g* to produce natural flow or there is insufficient liquid for submergence, then the excess gas flows from said well or wells into the gas line 82' and the gas from the gas well *f* flows into the gas line 84 and thence into the gas line 82' 45 to supply the wells that may be deficient in gas with gas for pumping.

The oil flows from the pump tubings 6 into the discharge pipes 48, thence to the oil line 49, thence to the gas trap 50, separator 50 63 and refining plant, and gas from these several sources of supply flows through the gas line 82 and is cooled, compressed and further cooled to remove condensates therefrom and to increase the pressure of the gas 55 to that required to pump any wells deficient in gas pressure and is then discharged into the gas line 82'.

The valve jacket 8 of the lowermost entry member in the well *e* is devoid of the valve 60 parts described as being in the other valve jackets and is provided at its lower end with a check valve 137 to prevent back pressure of the operating fluid on the fluid in the producing strata.

65 The gas line 82 may be provided at the

points where it enters the compressors 68, 70, with fluid-pressure regulators 139 so that the gas in said gas line between the compressor and all of the sources of gas supply connected to said line may be maintained at 70 somewhat greater pressure than atmospheric and thereby avoid sucking air into said compressors through any leaky joints in order to insure against the occurrence of explosions in the higher stages of compression. 75

If it is not desired to use the gas to operate the compressor 71' and cool the cooler 80', then said gases may be cooled by running them through a by-pass 140 of the gas line 82 and through the freezing vat 73. 80

If the pressure of gas in the well *e* becomes insufficient, because of lack of requisite submergence, to flow the liquid in the tubing 6, then the regulators 129, 130 close to shut off the oil and to shut off the operating gas supply by the gas line 82' so as to conserve said operating gas and pressure fluid in the producing strata. 85

If the pressure of gas in the well *e* becomes so great as would cause a blow-out of the 90 column of liquid in the tubing, then the regulator 133 opens and allows the gas under pressure to flow into the gas line 84, thence into the gas line 82 and thence to the compressor plant to have its pressure increased, or if the pressure of said gas is greater than that in the gas line 82' then said pressure opens the check valve 138 to allow said gas to enter the gas line 82' through the by-pass 132. 95

The regulators will be so adjusted that the surplus gas will be held in the wells until said gas reaches as great a pressure as desired in the gas well *f* and possible in the well *e* without preventing the desired yield 105 of oil from the producing strata of said well.

From this it is clear that, if said surplus gas is of sufficiently high pressure, said gas will be turned into the gas line 82' without having to go through the compressor plant; 110 and also that, even if it is necessary to raise said surplus gas to a higher pressure than the wells will produce consistent with their pumping, great economy of power is effected in the compressing plant. 115

By maintaining the surplus gas under relatively great pressures, it is noted that said gas will be relatively lean in condensates and therefore need not be passed through the condensing plant. 120

Heretofore it was necessary to run all of the gas at relatively low pressure through the compressing and condensing plants in order not to lose any of the condensates, but by this invention only a relatively small volume of relatively low pressure gas extremely rich in condensates is run through the compressing and condensing plants. 125

In event of the gas in the gas line 82' rising to a predetermined pressure desirable 130

for effecting the pumping operation due either to high pressure gas from any of the wells or to an excessive volume of low pressure gas passing through the compressor 70 5 and lower stage of the compressor 71, the regulator 83 closes to shut off said gas from the higher stage of the compressor 71.

The gas line 82 also connects to the motor end of the compressors 68, 69, thence connects to the cooler 80 so that the exhaust will cool said cooler, thence connects to coolers 78, 79 for the same purpose.

The sucker line 108 of the well *d* is connected, as shown in Fig. 11, by suitable driving connections 141 to a fluid-pressure operated engine 142 having its intake pipe 143 connected to the gas pipe line 82' and having its exhaust pipe 144 connected to the gas pipe line 82. With this construction it is seen that high pressure gas is first cooled to remove the condensates therefrom and is then used in an engine for performing useful work and then exhausts into the cooler to effect or aid in the cooling of said high pressure gas, thus effecting great economy 20 25 of the energy and useful products in the gas. The refrigerating, pumping and condensing operations are thus combined in a single plant, and the exhaust gases from the engine 142 after effecting the cooling operation may be used for fuel.

To prevent the well *e* or *g* "sanding," especially when it is not producing oil, the pump 110 will operate to continuously circulate oil from which the sand has been eliminated through the pump tubing to carry any sand that may be in the tubing therefrom into the oil pipe line, the sand thus discharged from the tubing being 30 35 eventually removed from the oil by action of the separator 63.

The detailed operation of the separating and refining devices above described is not entered into herein as their constructions 40 45 and operations are the subject matter of applications which I may file in the future. The system is provided with valves wherever desirable or necessary.

The patentable subject matter disclosed 50 55 and not claimed herein is in part the subject of my copending application for patent for well equipment, filed January 29, 1916, Serial No. 75,113.

I claim:

55 1. The method of pumping wells, which method consists in discharging fluid under lower pressure into the liquid in the pump tubing at a higher level to displace the liquid above said level, and then discharging 60 65 fluid under higher pressure at a lower level to displace the liquid above said lower level.

2. The method of pumping wells, which method consists in discharging fluid under 65 pressure into the liquid in the pump tubing

at a predetermined lower constant difference of pressures of said liquid, and shutting off said fluid from the tubing at a predetermined higher constant difference of pressures of said liquid.

3. The method of pumping wells, which method consists in discharging fluid under pressure from an outside source into the liquid in the pump tubing at a predetermined lower constant difference of pressures in said liquid at the discharge level, and shutting off said fluid from the tubing at predetermined higher constant difference of pressures at said discharge level.

4. The method of pumping wells, which method consists in storing in the well the gas produced by the well until there is flowing submergence, and then allowing said gas only at a predetermined difference of pressures of the gas and oil to discharge 85 into the pump tubing to lift the oil.

5. The method of pumping wells, which method consists in allowing the oil to flow from the producing strata into the pump tubing, providing a reservoir outside of the 90 pump tubing, allowing the gas from the producing strata only at a predetermined difference of pressures of the gas and oil to flow into said reservoir, shutting off communication between the tubing and reservoir until the gas is of sufficient volume and pressure to produce flow, and then allowing said gas to discharge into the pump tubing to lift the oil.

6. The method of pumping wells, which 100 method consists in distilling oil and saving the relatively dry gases resulting from the distillation, cooling said gases, compressing the gases thus cooled, cooling the gases thus compressed to condense distillates from said 105 gases, and then discharging the gases thus compressed and freed from distillates into the well to lift the oil.

7. The method of pumping wells, which method consists in distilling oil and saving 110 the relatively dry gases resulting from the distillation, cooling said gases, compressing the gases thus cooled, cooling the gases thus compressed to condense vapors from said gases, discharging the gases thus compressed 115 and freed from vapors into the well to lift the oil, cooling the gases issuing from the well with the oil, compressing said gases, then cooling the gases thus compressed to condense vapors from said gases, and discharging the gases thus cooled and freed from vapors into the well again to pump said well.

8. The method of pumping wells, which method consists in cooling the gases issuing 125 from the well, compressing the gases thus cooled, cooling the gases thus compressed to condense vapors from said gases, and discharging the gases thus compressed and freed from vapors into the well at a prede- 130

terminated difference of pressures of the gases and oil to lift the oil in said well.

9. The method of pumping wells, which method consists in cooling the gases issuing from the well, compressing the gases thus cooled, cooling the gases thus compressed to condense vapors from said gases, discharging the gases thus compressed and freed from vapors into the well to lift the oil in said well, cooling the gases issuing from the well with the oil, compressing said gases, then cooling the gases thus compressed to condense vapors from said gases, and discharging the gases thus cooled and freed from vapors into the well again to pump said well.

10. The method of pumping wells, which method consists in sealing the well to produce flowing submergence and gas pressure therein, and discharging fluid into the pump tubing at a predetermined difference of pressure of the fluid and liquid in the well to flow the liquid therein.

11. The method of pumping wells, which method consists in sealing the well to produce flowing submergence and gas pressure therein, and causing predetermined pressures of said gas to operate to discharge gas into the pump tubing first at one level and then at another to flow the liquid therein at said levels successively.

12. The method of pumping wells, which method consists in sealing the well to produce flowing submergence and gas pressure therein, and causing predetermined pressures of said gas to operate to discharge gas into the pump tubing first at a higher level and then at a lower level to flow the liquid therein at said levels successively.

13. The method of pumping wells, which method consists in sealing the well to produce flowing submergence and gas pressure therein, and discharging fluid into the pump tubing first at a lower level and then at a higher level to flow the liquid therein at said levels successively.

14. In combination, a well, means to hold the pressures of liquid and gas in the well, means for pumping liquid from the well by gas, and means to alter either of said pressures relative to the other of said pressures to obtain different velocities of discharge of fluid from the well.

15. In combination, a well provided with pump tubing, means opening to discharge an operating fluid under lower pressure into the pump tubing at a higher level to displace the liquid above said level, said means closing at higher pressure of the operating fluid, and means opening into the pump tubing at a lower level to displace the liquid above said lower level when the pressure of the operating fluid increases.

16. In combination, pump tubing having

entries at different levels, means to produce fluid pressure outside of the tubing at said entries, and a valve operated to open by higher pressure of said fluid to admit the fluid to the upper entry and operated to close by the hydrostatic pressure in the tubing to exclude said fluid.

17. In combination, pump tubing having entries at different levels, means to produce fluid pressure outside of the tubing at said entries, and a valve operated to open by pressure of said fluid to admit the fluid to the upper entry and operated to close by higher pressure of said fluid to exclude said fluid.

18. In combination, pump tubing having entries at different levels, means to produce fluid pressure outside of the tubing at said entries, and a valve operated to open by pressure of said fluid to admit said fluid to the upper entry and operated to close by the hydrostatic pressure in the tubing to exclude said fluid and operated to close by higher pressure of said fluid to exclude said fluid.

19. In combination, pump tubing having entries at different levels, means to produce fluid pressure outside of the tubing at said entries, a valve for the upper entry operated by the fluid pressure to open and operated by higher pressure to close, and a valve for the lower entry held closed by the hydrostatic pressure in the tubing when the upper valve is open.

20. In combination, pump tubing having entries at different levels, means to produce fluid pressure outside of the tubing at said entries, a valve for the upper entry operated by pressure of the fluid to close, and a valve for the lower entry operated by greater pressure of the fluid to open when the upper valve is closed.

21. In combination, pump tubing having entries at different levels, means to produce fluid pressure outside of the tubing at said entries, a valve for the upper entry operated by pressure of the fluid to close, and a valve for the lower entry operated by greater pressure of the fluid to open when the upper valve is closed, and operated by still greater pressure of the fluid to close.

22. In combination, casing, pump tubing in said casing, means to seal the space between the casing and tubing to form a reservoir for an operating fluid, and entry valves at different levels of the pump tubing to control the supply of operating fluid from the reservoir to the tubing.

23. In combination, casing, pump tubing in said casing, entry valves at different levels of the pump tubing to control the supply of operating fluid to the tubing, and a tube connecting said entry valves to one another and communicating with the casing.

24. A pumping system comprising well casings, pump tubings in said casings, means to seal the spaces between the casings and tubings to form reservoirs for an operating fluid, entry valves at different levels of the pump tubings to control the supply of operating fluid from the reservoirs to the tubings, and means connecting said reservoirs to one another.
- 10 25. A pumping system comprising well casings, pump tubings in said casings, entry valves at different levels of the pump tubings to control the supply of operating fluid to the tubings at said levels, and fluid-conducting means connecting the entry valve of one tubing to the entry valve of the other tubing.
- 15 26. A pumping system comprising pump tubing, oil distilling means connected to the pump tubing, gas cooling means connected to said distilling means, a gas compressor connected to said cooling means, other gas cooling means connected to the compressor, and gas-conducting means connecting said other cooling means to the pump tubing.
- 20 27. A pumping system comprising well casings, pump tubing in one of said casings, gas-cooling means connected to the other of said casings, a gas compressor connected to said cooling means, other gas-cooling means connected to the compressor, and gas-conducting means connecting said other cooling means to said pump tubing.
- 25 28. A pumping system comprising a well casing, pump tubing in said casing, gas-cooling means connected to the casing, a gas compressor connected to said cooling means, other gas-cooling means connected to said compressor, and gas-conducting means connecting said other cooling means to the pump tubing to flow the oil therein.
- 30 29. In combination, pump tubing having an entry member for an operating fluid, a pipe to supply the operating fluid to the entry member, a discharge pipe connected to the pump tubing, a fluid-pressure regulator for regulating the discharge from the discharge pipe, and a pipe connecting the operating-fluid supply pipe to the regulator so that the pressure in said supply pipe will operate the regulator.
- 35 30. In combination, pump tubing having an entry member for an operating-fluid, a pipe to supply the operating fluid to the entry member, a discharge pipe connected to the pump tubing, fluid-pressure regulators for the discharge and supply pipes respectively, and a pipe connecting the operating-fluid supply pipe to the regulators so that the pressure in said supply pipe will operate said regulators.
- 40 31. In combination, pump tubing, casing surrounding said tubing, a casing head for said casing, an entry member for the pump tubing to admit an operating-fluid to said tubing from the interior of the casing, a discharge pipe connected to the pump tubing, a pipe to supply the operating-fluid to the casing head, a fluid-pressure regulator for the discharge pipe, and a pipe connecting the supply pipe to the regulator so that pressure in said supply pipe will operate the regulator.
- 45 32. In combination, pump tubing, casing surrounding said tubing, a casing head for said casing, an entry member for the pump tubing to admit an operating-fluid to said tubing from the interior of the casing, a discharge pipe connected to the pump tubing, a pipe to supply the operating-fluid to the casing head, fluid pressure regulators for the discharge and supply pipes, and a pipe connecting the supply pipe to the regulators so that pressure in said supply pipe will operate the regulators.
- 50 33. In combination, pump tubing having an inlet member provided with a pressure controlled valve, a tube connected to the inlet member and provided with a check valve, and a pump to supply an operating fluid to said inlet member.
- 55 34. A pumping system comprising in combination with a well, a compressor connected by a gas pipe line to said well, a second gas pipe line connected to the well to furnish pumping-fluid to said well, and means operating to confine gas in the well until it reaches a predetermined pressure and to discharge said gas into the second gas pipe line when said predetermined pressure is reached.
- 60 35. A pumping system comprising in combination with a well, a refining plant connected by an oil pipe line to said well, a compressor connected by a gas pipe line to the refining plant to compress the gaseous products of the refining plant, a second gas pipe line connected to the well to furnish pumping-fluid to said well, and means operating to confine gas in the well until it reaches a predetermined pressure and to discharge said gas into the second gas pipe line when said predetermined pressure is reached.
- 65 36. A pumping system comprising in combination with a well, a refining plant connected by an oil pipe line to said well, a compressor connected by a gas pipe line to the refining plant to compress the gaseous products of the refining plant, a second gas pipe line connected to the well to furnish pumping-fluid to said well and connected to the compressor, and a regulator operated to open by fluid-pressure in the second gas pipe line on the well side of said line to admit the gas to said well.
- 70 37. A pumping system comprising in combination with a well, a compressor connected to the well to compress the gases produced

- from said well, a second compressor connected to the first compressor to further compress said gases, a condenser connected to the second compressor to remove the condensates from the gases, a gas pipe line connecting said condenser to the well to discharge a portion of said gases freed from condensates into the well and connecting said condenser to the motor end of the first compressor to operate said compressor with another portion of said gases.
38. A pumping system comprising in combination with a well, a compressor connected to the well to compress the gases produced by said well, condensing means connected to the compressor, a second compressor connected to the condensing means to further compress said gases, a condenser connected to the second compressor to remove the condensates from the gases, a third compressor connected to the condenser to further compress a portion of the gases freed from condensates and connected to the well to pump the liquid from said well, and a pipe connecting said condenser to the motor end of the second compressor to operate said compressor with another portion of the gases freed from condensates.
39. In combination, a well having a pump tubing and a conductor tube, a gas pipe line connected to said conductor tube, a dirt trap in said gas pipe line, and a fluid-pressure regulator in said line between the conductor tube and dirt trap, said dirt trap operating to prevent scale coming from the gas pipe line from clogging the regulator.
40. In combination, pump tubing, a conductor tube having gas inlets at both ends, an entry member between the ends of the conductor tube to admit gas therefrom to the pump tubing, and a valve in the entry member to regulate the flow of gas.
41. In combination, pump tubing, a conductor tube having gas inlets at both ends, an entry member between the ends of the conductor tube to admit gas therefrom to the pump tubing, and a valve in the entry member to prevent liquid passing from the pump tubing to the conductor tube.
42. In combination, pump tubing, means forming a gas reservoir, an entry member communicating with the pump tubing and reservoir, and means operating to effect and maintain a balance between the head of liquid in the tubing and the pressure of gas in the reservoir to hold the gas in said reservoir when the difference in pressures of gas and liquid exceeds a predetermined amount and to open communication between the reservoir and pump tubing when the difference between the pressures of the gas and liquid is less than said predetermined amount.
43. In combination, a well, an oil discharge pipe for said well, a gas pipe line connected to the well, and a regulator to control the flow of oil through said discharge pipe, said regulator being operated by the gas pressure in the gas pipe line.
44. A conductor tube, pump tubing, an entry member connecting the conductor tube to the pump tubing, a valve in the entry member operated to open against the head of liquid in the tubing by pressure of gas in the conductor tube and operated to close against said liquid head by higher pressure of said gas, and means to release gas from the conductor tube to lower the pressure and allow the first valve to be opened by the head of the liquid in the pump tubing.
45. The method of pumping oil, which method consists in compressing gases from a suitable source of supply, expanding the gases to create power, utilizing said power to pump oil from the well, and utilizing the expanded gases to cool the compressed gases from the source of supply to condense vapors from said compressed gases before said compressed gases are expanded as aforesaid.
46. The combination with pump tubing, of means connected therewith to separate oil, carbonaceous vapors and gases from one another while said oil, vapors and gases are under pressure, means to discharge the oil, carbonaceous vapors and gases under pressure into the separating means, and means for utilizing the gases thus separated to lift oil in the pump tubing.
47. The combination with pump tubing, of means connected therewith to separate water, oil, carbonaceous vapors and gases from one another while said water, oil, vapors and gases are under pressure, means to discharge the water, oil, carbonaceous vapors and gases under pressure into the separating means, and means for utilizing the gases thus separated to lift oil in the pump tubing.
48. The combination with pump tubing, of means connected therewith to separate sand, oil, carbonaceous vapors and gases from one another while under pressure, means to discharge the sand, oil, vapors and gases under pressure into the separating means, and means for utilizing the gases thus separated to lift oil in the pump tubing.
49. The combination with pump tubing, of means connected therewith to separate sand, water, oil, carbonaceous vapors and gases from one another while under pressure, means to discharge the sand, water, oil, vapors and gases under pressure into the separating means, and means for utilizing the gases thus separated to lift oil in the pump tubing.
50. The combination with pump tubing, of means connected to said tubing to separate oil, carbonaceous vapors and gases from one another while heated and under pressure,

means to heat said separating means, means to discharge the oil, vapors and gases under pressure into the separating means, and means for utilizing the gases thus separated 5 to lift oil in the pump tubing.

51. The combination with pump tubing, of means connected to said tubing to separate water, oil, carbonaceous vapors and gases from one another while heated and under 10 pressure, means to heat said separating means, means to discharge the water, oil, vapors and gases under pressure into the separating means, and means for utilizing the gases thus separated to lift oil in the 15 pump tubing.

52. The combination with pump tubing, of means connected to said tubing to separate sand, oil, carbonaceous vapors and gases from one another while heated and under pressure, 20 means to heat said separating means, means to discharge the sand, oil, carbonaceous vapors and gases under pressure into the separating means, and means for utilizing the 25 gases thus separated to lift oil in the pump tubing.

53. The combination with pump tubing, of means connected to said tubing to separate sand, water, oil, carbonaceous vapors and gases from one another while heated and 30 under pressure, means to heat said separating means, means to discharge the sand, oil, carbonaceous vapors and gases under pressure into the separating means, and means for utilizing the gases thus separated to lift 35 oil in the pump tubing.

54. The method of pumping wells, which method consists in causing gas to be held 40 in the well under pressure, discharging said gas into the liquid in the pump tubing at a predetermined lower constant difference of pressures of said liquid at the discharge level, and shutting off said fluid from the tubing at a predetermined higher constant difference of pressures of the fluid at the 45 discharge level.

55. The method of pumping a series of wells, which method consists in the formation 50 of a column of mixed oil and gas in balance with a column of oil in said wells so that the mixed column is raised, the cooling of the gas, the compressing of the gas, the separation of the compressed gas from the vapors carried thereby, and the return of at least a portion of the compressed gas

to one or more of the wells, wherein the 55 pressure is lower than desired, to pump said well.

56. The process of pumping which consists in applying an actuating fluid under pressure to the fluid to be pumped to effect 60 the pumping and stopping the pumping action by said actuating fluid when its pressure exceeds the resistance to the pumping action to a predetermined degree.

57. The process of pumping which consists in applying an actuating fluid under pressure to the fluid to be pumped to effect 65 the pumping, inaugurating the pumping action by said actuating fluid when its pressure equals that required to overcome the 70 resistance to the pumping action, and stopping the pumping action by said actuating fluid when its pressure exceeds the resistance to the pumping action to a predetermined degree. 75

58. In combination, well casing, a chamber in said casing, pump tubing in sections, one of said sections being connected to the lower end of said chamber and another of said sections extending through the upper 80 end and into the interior of said chamber, means in said chamber connected to the upper section to admit liquid thereto and exclude gas therefrom, a gas discharge pipe communicating with said chamber to draw 85 the gases therefrom, and a valve on said discharge pipe. 90

59. The method of pumping a well, which method consists in discharging gas into the pump tubing to lift the liquid in said tubing 90 from a lower level to a higher level and drawing off only a portion of said gas at the higher level, and then lifting said liquid to a still higher level. 95

60. The method of pumping a well, which method consists in lifting liquid in the well from a lower level to a higher level, discharging gas into the pump tubing at said higher level to lift said liquid to a still higher level, and trapping and drawing off 100 some of said gas at said still higher level.

In testimony whereof, I have hereunto set my hand at Los Angeles, California, this 22nd day of October 1915.

WARREN R. GREENLEE.

In presence of—

GEORGE H. HILES,
A. F. SCHMIDTBAUER.
